UNITED STATES PATENT OFFICE.

SIMEON S. JACKSON, OF HYDE PARK, BOSTON, MASSACHUSETTS, ASSIGNOR TO THE STAFFORD COMPANY, OF READVILLE, BOSTON, MASSACHUSETTS, A CORPORATION OF MASSACHUSETTS.

SHIPPER MECHANISM FOR LOOMS.

Application filed June 15, 1922. Serial No. 568,512.

To all whom it may concern:

Be it known that I, SIMEON S. JACKSON, a subject of Great Britain, residing at Hyde Park, Boston, in the county of Suffolk, State 5 of Massachusetts, have invented a certain new and useful Improvement in Shipper Mechanism for Looms, of which the following is a specification, reference being had therein to the accompanying drawings.

10 The invention has reference to the devices which are employed in looms for the purpose of shipping the driving power on, and unshipping the driving power, as well as controlling the action of the brakes. It has 15 relation to the rockshafts which in the case of some looms extend across the front of a loom from one side of the latter to the other side thereof, and by means of which shipper and brake mechanisms located at one side are 20 controlled by stop-motion connections, the latter sometimes located at the opposite side of the loom. The invention provides a new and improved shipper-mechanism controlling rockshaft which, in addition to securing 25 other advantageous results gives the weaver greater control of the loom. The invention has been designed more especially for use in looms of the high or elevated take-up roll type, but is not restricted to use in that type 30 alone of looms.

The accompanying drawings show an illustrative embodiment of my invention, in which,—

Fig. 1 is a plan view of certain parts at 35 the forward end of a loom, including the said illustrative embodiment of my invention, but with the shield for the take-up roll omitted.

Fig. 2 is a front view of the same, showing 40 the said shield.

Fig. 3 is a side elevation of the parts at the left-hand side of Figs. 1 and 2.

Having reference to the drawings:—

As heretofore in the art, the high take-up 45 roll 1 is journaled in elevated bearings in connection with the forward portion of the loom-frame, it being so located that the cloth α passes to the upper portion of its periphery directly from the fell, and thence 50 to the cloth-roll 2 upon which it is wound, said cloth-roll 2 being driven by peripheral contact with the take-up roll 1. At 21, 21, are the upwardly-pressed slides engaging with the journals 22, 22, of the cloth-roll

and serving to keep the periphery of the 55 cloth-roll pressed against that of the take-up roll as in Fig. 3. At 4, Figs. 2 and 3, is shown the shield for the take-up roll, such shield being omitted from Fig. 1. The shipper-handle 5 is as usual mounted at the left 60 side of the loom upon the pivot 6 projecting from the loom-side 7; it is coupled in well-known manner by its projecting pin 51 to the slotted upper end of the link 8 extending to the clutch and brake mechanism (not 65 shown), and is provided at its lower end with the usual hooked portion 59 for engaging the brake-lever after the said lever has been lifted by the weaver and holding 70 it to keep the brake free and allow the loom to be turned over by hand. In the forward position occupied by shipper-handle 5 in the drawings its pin 51 supports link 8 in a relatively elevated position, with the brake off and the driving power on, as during the 75 running of the loom. At the right-hand side of the loom are the connections through which the warp-stop-motion mechanism (not shown) effects the unshipping, etc., of the loom, such connections being represented by the link 9 through which the warp-stop 80 mechanism operates to knock off the shipper-handle when such mechanism detects breakage of a warp-thread.

My invention comprises a new and improved form of shipping rock-shaft 10, mounted in elevated bearings at the front of the loom extending across the loom from side to side, and which is actuated by the link 9, to trip the shipper-handle 5 85 in order to stop the loom when breakage of a warp-thread occurs. Heretofore, the rock-shaft employed has usually been a straight 90 shaft, and has had no other utility than its elemental one of tripping the shipper-handle or other shipper devices under the control of the warp-stop-motion means.

In accordance with my invention I form the rockshaft 10 with a forwardly cranked or offset intermediate portion exceeding the 100 full length of the cloth-roll 2. This form allows it to extend across the loom with its said intermediate portion forward of the said rolls 1 and 2, and clearing the full cloth-roll, and at the same time permits its bearings to be located as shown in or in connection with the loom sides 7, 7, in relatively rearward positions in line with points 105

within the diameter of a partly-filled cloth-roll 2. That is to say, the form referred to enables the said bearings to be located at a distance from the axis of the cloth-roll 5 which is less than the radius of the cloth-roll at a comparatively early stage in the winding of said roll. Thus by my invention I avoid projection of the bearings of the said rockshaft at the front of the loom into the 10 space where the weaver stands and passes back and forth.

The cranking of the intermediate portion of the rockshaft 10 enables the weaver to rock the said rockshaft from any point at 15 which he may be standing across the front of the loom, and through such rocking actuate the shipper devices to throw the driving power on and off, to start and stop the loom. This renders it unnecessary for him to step 20 to the side of the loom at which the shipper-handle is located. In the present instance I employ as coupling means between the rockshaft 10 and the shipper-handle 5 the arm 12 fixed upon one end of the rockshaft 10 outside 25 of the loom-frame, and the link 13 connecting the end of said arm 12 with the projecting pin 51 upon the shipper-handle 5.

The link 9 from the warp-stop mechanism is attached to an arm 91 fixed upon the 30 right-hand end of the said shipper-actuating rod.

Of great value and convenience is the utilization of the rock-shaft 10 as a shipper-actuating means, it affording the weaver 35 more perfect control of the loom. The great importance of enabling the weaver to stop the loom instantly from any point in front thereof at which he may be standing will be realized.

40 What is claimed as the invention is,—

1. In a loom, the combination with a high take-up roll, a cloth-roll driven by frictional contact with said take-up roll, and a shipper-handle at one side of the loom, of a rockshaft extending across the front of the loom-frame, operatively connected with the shipper-handle, and having a cranked intermediate portion exceeding the length of the wound roll of cloth, adapted to clear said

roll, and by means of which the said rockshaft 50 may be rocked manually from any point in front of the loom to move the shipper-handle to start or stop the loom.

2. In a loom, in combination, a shipper-handle, a rockshaft extending across the 55 front of the loom, directly connected with said shipper-handle, and having an elongated cranked intermediate portion accessible to the weaver across the front of the loom by means of which the rockshaft may be 60 rocked by the weaver from any point in the width of the loom to actuate the shipper-handle to start and stop the loom.

3. In a loom, in combination, a shipper-handle at one side of the loom, warp-stop-motion connections at the other side thereof, and a rockshaft directly connected at one end with said shipper-handle and at the other with said warp-stop-motion connections, and having a cranked intermediate 70 portion accessible to the weaver across the front of the loom, by means of which the weaver while standing in front of the loom may manually rock the said rockshaft to throw said shipper-handle to start and stop 75 the loom.

4. In a loom, the combination with a shipper-handle at one side of the loom, a cloth-roll, and bearings adjacent the opposite ends of the said cloth-roll located at a distance 80 from the axis of the cloth-roll which is less than the radius of the wound mass at an intermediate stage in the winding-up of the cloth, of a rockshaft mounted in the said bearings, operatively connected with the shipper-handle, and having a cranked intermediate portion exceeding the length of the wound roll of cloth, adapted to clear said roll, and which may be grasped by the 85 weaver at any point across the front of the loom to rock the rockshaft manually to move the shipper-handle to start or stop the loom.

In testimony whereof I affix my signature in presence of two witnesses.

SIMEON S. JACKSON.
